(57) **CLAIM**

The ornamental design for a lighter, as shown and described.

DESCRIPTION

FIG. 1 is a rear elevational view of the lighter attached to a key chain (key chain not considered part of design);
FIG. 2 is a side elevational view of the lighter attached to a key chain (key chain not considered part of design);
FIG. 3 is a bottom plan view of the lighter;
FIG. 4 is a top plan view of the lighter attached to a key chain (key chain not considered part of design);
FIG. 5 is another side elevational view of the lighter attached to a key chain (key chain not considered part of design);
FIG. 6 is a front elevational view of the lighter attached to a key chain (key chain not considered part of design);
FIG. 7 is a perspective view of the lighter attached to a key chain (key chain not considered part of design); and,
FIG. 8 is another perspective view of the lighter attached to a key chain (key chain not considered part of design).
The broken lines are shown for illustrative purposes only and form no part of the claimed design.
